UNITED STATES PATENT OFFICE.

NIXON THOMAS, OF DUPONT, INDIANA.

WASHING-MACHINE.

SPECIFICATION forming part of Letters Patent No. 228,139, dated May 25, 1880.

Application filed October 8, 1879.

To all whom it may concern:

Be it known that I, NIXON THOMAS, of Du-
pont, in the county of Jefferson and State of
Indiana, have invented a new and Improved
5 Washing-Machine, of which the following is a
specification.

Figure 1 is a side elevation of the device,
partly in section. Fig. 2 is a plan of the de-
vice. Fig. 3 is a detail view, shown in eleva-
tion, to illustrate the relative position of the
stirrup.

Similar letters of reference indicate corre-
sponding parts.

The object of this invention is to provide
15 an improved device for increasing the effi-
ciency of those washing-machines that operate
by pounding the clothes.

A represents the support, that is composed
20 of the main arm *a* and the side arms, *b b*,
which are pivoted to it at *c*. All these arms
a b b are curved, so that when secured to the
edge of the tub they may support the plun-
gers centrally over the tub, and all of them
25 are provided on their inner faces, near their
lower ends, with studs *d*, on which are piv-
oted the jaws *f*.

To secure the device in position the edge of
the tub *B* is grasped between the jaws *f* and
the ends of the arms *a b b*, and the thumb-
30 screws *g* turned so as to sufficiently throw out
the tops of the buttons *f*, and thereby force
inward their bottoms.

The forked upper end of the main arm *a* is
pivoted to the hanging bent arm *C*, so that it
35 can move in a vertical plane. This arm *C*
supports the guiding-rod *D*, that extends per-
pendicularly downward. Immovably fixed on
the rod *D* is the hanger *E*, to whose depend-
ent slatted end is pivoted the forked lever *F*
40 by a bolt, *h*, that passes through the slot *i*.

Encircling the guiding-rod *D*, between the
arms of the hanger *E*, is the stirrup *G*, whose
downward-bent arms are fastened at their

ends to the cross-head *H*, that is provided with
the sockets *k*, in which the handles *l* of the 45
plungers *I* are held by the set-screws *m* in such
a manner that the said plungers *I* can be
turned around to any desired position.

To the arms of the stirrup *G* the arms of
the forked lever *F* are fastened, so that by 50
means of the said lever *F* the cross-head *H*
and plungers *I* can be moved up and down in
the operation of washing; and at any time
during the washing operation the operator can
at will, and by means of the lever *F*, give a 55
half-revolution to the rod *D* and its connec-
tions in order to cause the plungers *I* to strike
upon fresh surfaces of the clothes.

By withdrawing the pin *n*, that rigidly holds
the arm *C* in position, as shown in the draw- 60
ings, the said arm *C* and all its attachments
may be turned upward clear of the tub and
its contents.

Having thus described my invention, what
I claim as new, and desire to secure by Letters 65
Patent, is—

1. The within-described washing-machine,
composed of the support *A*, hanging arm *C*,
hanger *E*, stirrup *G*, cross-head *H*, lever *F*,
and plungers *I*, constructed and arranged sub- 70
stantially as herein shown and described.

2. In a washing-machine, the support *A*,
composed of curved arms *a b b*, pivoted to-
gether and provided with studs *d*, jaws *f*, and
thumb-screws *g*, substantially as herein shown 75
and described, in combination with the arm *C*,
that supports the operating parts of the ma-
chine, as herein set forth.

3. The combination, with plungers *l I*, of the
rod *D*, slotted hanger *E*, lever *F*, and stirrup 80
G, as and for the purpose specified.

NIXON THOMAS.
